ENGINE CONSTRUCTION

Edwin S. Hall, New Haven, Conn.

Application August 9, 1939, Serial No. 289,149

7 Claims. (Cl. 123—58)

This invention relates to engine constructions, and more especially to the fixed parts of engines. It is particularly advantageous in engines of types having two sets of cylinders facing each other, as for example: horizontal opposed engines, and engines having cylinders parallel to the shaft and commonly known as barrel type or round engines. The invention may conveniently be described as applied to the normal type of barrel engine, that type having two similar groups of cylinders with a single reciprocating-rotary conversion mechanism between them, but it is understood that it may be applied also to various other types of engines.

In the normal type of round engine, it would be desirable to form both cylinder blocks integral, insuring the alignment of opposing cylinders and an oil-tight engine. However, it is not ordinarily possible with such an integral construction to assemble the reciprocating-rotary conversion mechanism. It has been common practice to split such an engine either longitudinally or transversely to permit assembly. The longitudinal split is undesirable because of lack of symmetry of the major parts and difficulties of assembly. The transverse split has the advantage of axial symmetry of the cylinder blocks, but great care must be taken that the opposed cylinders be exactly coaxial for the proper operation of the common piston member therein. An object of this invention is to provide a construction in which opposite cylinders may be integral, insuring their alignment, while avoiding the difficulties of the longitudinal split mentioned above, the cylinder units being individual and assembled radially relative to the reciprocating-rotary conversion mechanism. Another object is to provide convenient and practical means for insuring an oil-tight closure about the working parts of an engine constructed with integral cylinder units in which double-ended piston members are operable. Another object is to provide easily replaceable cylinder units.

Briefly described, the invention comprises integral cylinder units extending between two similar casing members each common to all the cylinder units and forming therewith a rigid structure, with a cover extending from one casing member to the other and therewith forming a closure about the individual cylinder units.

In both the normal and opposed-piston types of round engines, it is economical and desirable to use two separate similar frame members each common to the several cylinders and containing the bearings which support the shaft. An object of this invention is to provide practical constructions of this character, with a closure extending from one common member to the other enclosing the cylinder members and the reciprocating-rotary mechanism.

A further object is to provide a type of construction for round engines which is especially practical for use in the production of large engines.

These and other objects of the invention will appear more clearly from the following specification and from the drawings in which

Fig. 1 is a longitudinal section thru an engine constructed in accordance with the invention;

Fig. 2 is a transverse section thru the fixed parts of Fig. 1;

Fig. 3 is a longitudinal section of another embodiment of the invention;

Fig. 4 is a transverse section taken on the line 4—4 of Fig. 3;

Fig. 5 is a longitudinal section of another embodiment of the invention;

Fig. 6 is a transverse section taken on the line 6—6 of Fig. 5;

Fig. 7 is a longitudinal section of another embodiment of the invention;

Fig. 8 is an end view of Fig. 7; and

Fig. 9 is a transverse section taken on the line 9—9 of Fig. 7.

Referring to Figs. 1 and 2, shaft 10 is supported in ball bearings 11 and 12 mounted in cylinder blocks 13 and 14. Cylinders 15 are tubular members each extending from one cylinder head to the other opposite head and forming a "wet liner" sealed inwardly by soft packing 16 of rubber or similar material and at the ends by being drawn down against soft metal washers 17 by thru-bolts 18 and nuts 19 which draw cylinder blocks 13 and 14 together. Bolts 18 are symmetrically spaced about each cylinder sleeve 15 as shown in Fig. 2. Cylinders 15 are cut away symmetrically in their mid-region, providing for the interconnection of piston member 20 with shaft 10 by means of wobbler 21 and its cooperating mechanism in a well-known manner.

While cylinder sleeve 15 extend thru the water jacket as "wet liners," bolts 18 extend thru bosses 28 so that the coolant does not touch the bolts. Bosses 28 also serve to stiffen cylinder blocks 13 and 14. Bolts 18 are preferably necked down to the root diameter of their threads throughout most of their lengths, as shown in Fig. 1. Cylinder sleeves 15 may be made of steel or similar material having similar expansion coefficient with that of bolts 18.

At assembly, piston member 20 is assembled in its cylinder sleeve 15, and the piston and cylinder then assembled radially onto the wobbler mechanism, and then both are moved axially into one of the cylinder blocks. After the several cylinders with their corresponding pistons are thus assembled in one cylinder block, the other block is assembled, bolts 18 inserted, and drawn up by nuts 19, seating all cylinder sleeves 15 on their soft metal washers 17. Cylinder blocks 13 and

14 may be made of cast aluminum or similar material, and ordinarily would not have the same coefficient of expansion as that of sleeves 15 and bolts 18, so a space is left between blocks 13 and 14. Casing 24 is clamped around flanges of cylinder blocks 13 and 14, casing 24 extending from block 13 to block 14 and forming therewith an oil-tight closure around sleeves 15 and the wabbler mechanism.

Nuts 19 may be of a common type, but it is preferable to seat them in counterbores 29 as shown in Fig. 1, hexagonal sockets 27 being formed in nuts 19 for the application of a hexagonal bar wrench. Counterbores 29 may also be tapped out for hollow plugs 23, which may be screwed in when it is desired to disassemble, nuts 19 being screwed outwardly against plugs 23 to "jack" cylinder blocks 13 and 14 apart, making it easier to draw them off from cylinder sleeves 15.

Cylinder sleeves 15 are turned down on the outside to remove useless weight and to permit the coolant to flow freely between them and bosses 28 which house bolts 18, bosses 28 being trimmed to pass the largest outside diameter of sleeves 15 when the holes are bored in blocks 13 and 14 for sleeves 15. Sleeves 15 are left full size at their head ends where pressures are highest, and toward the central portion where grooves for the soft packing 16 are provided and where sleeves 15 are cut away to permit attachment of piston members 26 with the wabbler 21.

Referring to Figs. 3 and 4, shaft 30 is supported in journal bearings 31 formed in inwardly extending portions of cylinder head members 33 and 34. Axial movement of shaft 30 is prevented by thrust bearing 32. Cylinders 35 are tubular members each extending from one cylinder head member to the other and each having its own water jacket 36 forming an annular passage from the water jacket chambers of one cylinder head member to those of the other, the interconnecting passages being thru gaskets 37 clamped between the ends of cylinder members 35 and cylinder head members 33 and 34 by bolts 38. Cylinder members 35 are seated in notches 39 formed in the inwardly projecting portions of cylinder head members 33 and 34, which together with bolts 38 produce a rigid structure of the whole. An oil-tight closure is formed by casing 44 extending from one cylinder head member 33 to the other 34, enclosing cylinder members 35 and the reciprocating-rotary mechanism.

Each piston member 40 carries two rollers 41 mounted on pins 42 for coaction with cam 43 which is fixed on shaft 30, these parts forming the reciprocating-rotary mechanism by which piston motion is converted into rotation of shaft 30.

At assembly, pistons 40 with their rollers 41 and pins 42 in place, are inserted in operable position in cylinders 35, which are then assembled radially in notches 39 of cylinder head members 33 and 34 which have been assembled previously on shaft 30. Then by bolts 38, the cylinder head members are drawn together upon cylinder members 35, whereupon casing 44 is added to form a closure between cylinder head members 33 and 34 enclosing cylinders 35 and the reciprocating-rotary mechanism.

The construction of the fixed parts of the engine shown in Figs. 7, 8, and 9, is essentially similar to that of Figs. 3 and 4, but the cylinders 75 are ported for uni-flow two-stroke operation. While the reciprocating-rotary mechanism of 75

Figs. 3 and 4 is of the cam type, that of Figs. 7, 8, and 9 is of the wabbler type.

Shaft 70 is carried in journal bearings 71 formed in inwardly extending portions of valve casing members 73 and 74, axial movement of shaft 70 being prevented by thrust faces 72. Cylinder members 75 are tubular members extending from one valve casing member 73 to the other 74. Cylinder members 75 are seated in notches 79 formed in the inwardly projecting portions of valve casing members 73 and 74, and are clamped therein by bolts 78 and also by segments 76 and bolts 77. Segments 76, together with the walls in which notches 79 are formed, constitute bulkheads isolating the intake chamber 81 from the "crankcase" 82. Casing 84 is wrapped around the engine and clamped onto soft packings 83 in grooves in casing members 73 and 74 and in segments 76 by the action of clamp bands 87 drawn up by bolts 88.

Each cylinder member 75 has inner and outer cylindrical walls, the inner wall 85 forming the cylinders themselves discontinuous in the central region. The outer wall 86 forms water jackets for cylinders 85 and in the central region forms a cylindrical crosshead guide 89 coaxial with cylinders 85.

Each piston member comprises pistons 80 bolted to a central crosshead 90 by bolts 91, pistons 80 being operable in cylinders 85 and crosshead 90 in crosshead guide 89. In a cylindrical bore thru crosshead 90, wristpin carrier 92 is operable, wristpin 93 being fixed therein. Wabbler arm 94 operably engages wristpin 93, and is bolted to wabbler 95 by bolts 96. Wabbler 95 is operably mounted on swashplate 97 fixed upon shaft 70.

To assemble, swashplate 97 is fixed on shaft 70, and the body only of wabbler 95 is placed in operable position upon swashplate 97. Valve casing members 73 and 74 are slipped onto shaft 70, cylinder members 75 are inserted radially into notches 79 and bolted to casing members 73 and 74 by bolts 78. Segments 76 are bolted in by bolts 77, with suitable packing. Pistons 80 are inserted thru the handholes in cylinder members 75, after which each crosshead 90 is inserted edge-wise and rotated into operable position in its crosshead guide 89; then pistons 80 and crosshead 90 are clamped together by bolts 91.

Wabbler arm 94 is assembled on wristpin 93 and the latter fixed in its carrier 92, whereupon this wabbler arm assembly is inserted thru the handhole in cylinder member 75 and attached to wabbler 95 by bolts 96.

Soft packings 83 are placed in their grooves, and casing 84 wrapped around the whole, forming an oil-tight closure extending from one casing member 73 to the other 74.

Figs. 5 and 6 illustrate the fixed parts only for an engine having pistons and wabbler mechanism similar to those of Figs. 7, 8, and 9. The structure comprises cylinder blocks 53 and 54, in which cylinders 55 and journal bearings 51 are formed. Crosshead guides 56 are tubular members extending from one cylinder block 53 to the other 54. Crosshead guide tubes 56 are flanged at both ends and are clamped to cylinder blocks 53 and 54 by clamps 57 and bolts 58, after which casing 66 is wrapped around blocks 53 and 54 and clamped to form an oil tight closure therewith.

Having thus described the invention, it is clear that the objects thereof as stated have been attained in a practical and advantageous manner. While specific embodiments of the invention have been shown, it is understood that

changes may be made in the construction and in the arrangement of the parts without departing from the spirit and scope of the following claims.

I claim:

1. In an engine, two similar casing members spaced apart, chambers for cooling liquid formed in said casing members, cylindrical bores in said casing members in coaxial pairs facing each other, individual cylinder sleeves received by said pairs of bores, thru-bolts adjacent said sleeves drawing said casing members together tightly upon said sleeves, means for sealing said sleeves in said bores so that said sleeves form "wet liners" in said liquid chambers formed in said casing members, and casing means extending from one of said casing members to the other and therewith forming a closure about said sleeves.

2. An engine comprising two similar casing members, chambers for cooling liquid formed in said casing members, a shaft, bearings for said shaft in said casing members, a reciprocating-rotary conversion mechanism operable with said shaft and positioned between said casing members, cylindrical bores in said casing members in coaxial pairs facing each other, individual cylinder sleeves one in each of said pairs of bores, thru-bolts adjacent said sleeves drawing said casing members together tightly upon said sleeves, means for sealing said sleeves in said bores so that said sleeves form "wet liners" in said liquid chambers formed in said casing members, double-ended piston members operable in said sleeves and operably connected to said shaft by said conversion mechanism, and casing means extending from one of said casing members to the other and therewith forming a closure about said sleeves and said mechanism.

3. In a normal barrel type engine, two similar casing members, chambers therein for the cooling medium, a shaft, bearings for said shaft carried by said casing members, a reciprocating-rotary conversion mechanism operable with said shaft and positioned between said casing members, cylindrical bores in said casing members in coaxial pairs facing each other and parallel to said shaft, individual cylinder sleeves one in each of said pairs of bores, thru-bolts adjacent said sleeves drawing said casing members together tightly upon said sleeves, means for sealing said sleeves in said bores so that said sleeves form "wet liners" in said cooling medium chambers, double-ended piston members operable in said sleeves and operably connected to said shaft by said conversion mechanism, and casing means extending from one of said casing members to the other and therewith forming a closure about said sleeves and said mechanism.

4. In a normal barrel engine, a shaft, two similar casing members coaxial therewith, cylindrical bores in said casing members in two sets facing each other and parallel to said shaft, individual cylinder units seated in said bores and connecting said casing members, thru-bolts adjacent said cylinder units for drawing said casing members together upon said cylinder units thereby fastening said casing members together into a rigid structure, and means associated with said thru-bolts by which said casing members may be forced apart upon disassembly.

5. In a normal barrel-type engine having a shaft and cylinders parallel thereto, with cylinder heads at both ends thereof, and double-ended piston members operable in said cylinders and operably connected to said shaft: a construction for the fixed parts of said engine comprising two

similar casing members spaced apart and coaxial with said shaft; individual cylinder members parallel to said shaft and extending from one of said casing members to the other; and, for receiving each end of each of said cylinder members, a plurality of substantially cylindrical seats formed in each of said casing members, said seats being coaxial but axially spaced apart to embrace axially spaced areas on the cylinder member seated therein to insure and maintain alignment thereof parallel to said shaft; and means for securing said cylinder members in said seats thereby fastening said casing members together upon said cylinder members in a rigid structure with said cylinder members in compression between said casing members.

6. In a normal barrel-type liquid-cooled engine having a shaft and cylinders parallel thereto, with cylinder heads at both ends thereof, and double-ended piston members operable in said cylinders and operably connected to said shaft: a construction for the fixed parts of said engine comprising two similar casing members spaced apart and coaxial with said shaft; a chamber for cooling liquid in each of said casing members; individual cylinder members parallel to said shaft and extending from one of said casing members to the other; and, for receiving each end of each of said cylinder members, a plurality of substantially cylindrical seats formed in each of said casing members, said seats being coaxial but axially spaced apart to embrace axially spaced areas on the cylinder member seated therein to insure and maintain alignment of said cylinder member and permitting direct contact of the cooling liquid of said chamber with said cylinder member between said axially spaced areas; means for sealing said axially spaced areas in said seats to prevent leakage of said liquid; and means for securing said cylinder members in said seats thereby fastening said casing members together upon said cylinder members in a rigid structure with said cylinder members in compression between said casing members.

7. A normal barrel-type liquid-cooled engine comprising two similar frame parts spaced apart; a chamber for cooling liquid in each of said frame parts, a shaft; bearings for said shaft in said frame parts; individual cylinder members extending from one of said frame parts to the other; and, for each end of each of said cylinder members, a plurality of substantially cylindrical seats formed in each of said casing members, said seats being coaxial but axially spaced apart to embrace axially spaced areas on the cylinder member seated therein to insure and maintain alignment of said cylinder member and permitting direct contact of the cooling liquid of said chamber with said cylinder member between said axially spaced areas; means for sealing said axially spaced areas in said seats to prevent leakage of said liquid; means for securing said cylinder members in said seats thereby fastening said casing members together upon said cylinder members in a rigid structure; pistons operable in said cylinder members; a reciprocating-rotary conversion mechanism operably connecting said pistons with said shaft and positioned between said frame parts; and a cover extending from one of said frame parts to the other and forming therewith a closure about said cylinder members and said mechanism with said cylinder members in compression between said casing members.
